CARRYING CASE

Robert H. Burdge and Stanley M. Speas, Kansas
City, Mo.

Application April 3, 1937, Serial No. 134,887

3 Claims. (Cl. 190—17)

Our invention relates to a carrying case having compartments and movable trays in which toilet and other personal articles may be conveniently carried. An object of the invention is the provision of means whereby when the lid of the case is opened, it will swing the trays upwardly to a position where their contents will be readily accessible, and conversely when the lid is lowered it will swing the trays downwardly to permit the lid to close.

Other objects will hereinafter appear and in order that the invention may be fully understood, reference will now be had to the accompanying drawing, in which:

15 Fig. 1 is a perspective view of the case with the lid thereof in open position.

Fig. 2 is an enlarged cross section on line 2—2 of Fig. 1.

Fig. 3 is a longitudinal section of the case with 20 the lid in closed position.

Fig. 4 is a detail perspective of part of the means through which the movements of the trays are controlled by the lid.

Referring in detail to the different parts, 25 2 designates the body of the case which is divided into a relatively large central compartment 4 and two narrow end compartments 6 by means of transverse partitions 7.

8 designates a lid which is connected to the 30 rear wall of the body 2 by hinges 10, so that said lid may be swung to either an open or a closed position. The lid 8 is provided with a fixedly mounted mirror 12 and reinforced by two transverse partitions 14, which latter are slightly 35 farther apart than the partitions 7 to avoid contacting with the same when the lid 8 is closed, as shown by Fig. 3.

16 designates a pair of trays which are mounted 40 to swing transversely to the movement of the lid 8 in their passage to and from the respective compartments 6. This result may be accomplished by operably connecting the trays 16 to the body 2 in different ways. For example we have shown the bottoms 18 of the trays 16 connected 45 to the respective end walls of the body 2 by hinges 20. Each bottom 18 has an extension 21 which projects beyond the adjacent side wall 22 of each tray 16 to close the space between the trays and the associated partitions 7, Fig. 1, so that articles may not fall into the compartments 6 when the trays are in raised position. Each tray 16 is provided with a cover 24 operably connected thereto and adapted to prevent articles 50 from falling out of the trays when the same are

swung inwardly to the respective positions shown by Fig. 3.

Different means may be employed whereby the movements of the trays 16 are automatically controlled through the movements of the lid 8. For example we have shown such means in the form of links 26 and two sets of hinges 32 and 34. Each hinge comprises two leaves, one leaf of each hinge 32 being connected to the respective partitions 14 and the other connected by a pivot 28 10 to the adjacent end of the respective links 26. One leaf of each hinge 34 is connected to the adjacent tray 16 and the other connected by a pivot 30 to the end of the adjacent link 26. The hinges 32 are arranged at suitable angles to the 15 hinges 34 to permit the trays to move at right-angles or transversely to the movement of the lid 8.

With the foregoing arrangement it is apparent that when the lid 8 is raised to open position 20 it will, through the intermediary of the links 26 and hinges 32 and 34, swing the trays 16 upwardly and outwardly a quarter of a revolution to the position shown by Fig. 1, and conversely when the lid is closed it will swing the trays down- 25 wardly into the compartments 6.

The links 26 are of such length as to check the movement of the lid 8 when it is swung open to the rearwardly inclined position shown by Figs. 1 and 2, where it presents the mirror at a 30 convenient angle for use.

From the foregoing description taken in connection with the drawing, it is apparent that we have provided an attractive case which is well adapted for the purpose intended, and while we 35 have shown one form of the invention, we reserve all rights to such other forms and modifications as properly fall within the spirit and scope of the invention as claimed.

Having thus described our invention, what we 40 claim and desire to secure by Letters Patent is:

1. A case comprising a body, a lid hinged to said body, a tray arranged in one end of the body and adapted to swing transversely to the movement of the lid when the same is opened or 45 closed, means operably connecting the tray to said body to permit the tray to swing downward when the lid is closed or upward when the lid is opened, a pair of two-leaf hinges, one having a leaf secured to the body and the other a leaf secured to the lid, and a link operably connected to free leaves of the hinges and adapted to co-operate therewith in swinging the tray when the lid is opened or closed. 50

2. A case comprising a body, a lid hinged to 55

said body, a tray arranged transversely in each end of the body and adapted to swing transversely to the movement of the lid when the same is moved to open or closed position, means operably connecting each tray to the body to allow the trays to swing downward when the lid is closed or upward when the lid is opened, two sets of two-leaf hinges, one set having a leaf secured to the body and the other set having a leaf secured to the lid, and a pair of links pivotally connected at their ends to the respective free leaves of the hinges and adapted to cooperate therewith in swinging the trays when the lid is opened or closed.

3. A case comprising a body, a lid operably connected to said body, a tray operably connected to the body and adapted to swing transversely to the movement of the lid when the same is opened or closed, a link actuated by the lid 5 and adapted to control the movements of the tray, a two-leaf hinge having one leaf fixed to the tray and the other leaf operably connected to the link, and another two-leaf hinge, having one leaf fixed to the lid and the other leaf operably 10 connected to the link.
